CLAIM

The ornamental design for a sound box, as shown and described.

DESCRIPTION

FIG. 1 is a top, front and right side perspective view of a sound box, showing my new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof; and,
FIG. 7 is a bottom plan view thereof.

The broken lines in the drawings depict portions of the sound box that form no part of the claimed design.
